UNITED STATES PATENT OFFICE

GUST POULAS, OF CLEVELAND, OHIO, ASSIGNOR OF FORTY PER CENT TO THEODORE BIBICOS, OF CLEVELAND, OHIO

PREVENTION OF IRON AND STEEL SLUGS ENTERING SLOT MACHINES

Application filed September 9, 1932. Serial No. 632,345.

This invention relates to fraud preventive devices to prevent the insertion of iron, steel, or other magnetic slugs into slot machines.

An object of the invention is to provide an improved, simple and effective device for this purpose, characterized by the use of a magnet fixed with one of its poles beside the coin slot, and a movable or pivoted magnetic lock member or stop which is positioned between the poles and which is normally held by the attraction of the magnet out of line with the slot, but which upon the insertion of a magnetic slug will swing out across the slot and stop the passage of the slug, the passage of a non-magnetic coin being nevertheless permitted.

In the accompanying drawing Fig. 1 is a top view of a box made of non-magnetic material which contains the mechanism. Fig. 2 is a side view of Fig. 1 with parts in section and shows the position of the stop member when a coin is inserted. Fig. 3 is a view similar to Fig. 2 showing a magnetic slug stopped by said member. Fig. 4 is a side elevation 25 of the stop member and the frame for supporting it. Fig. 5 is a section on the line 5—5 of Fig. 2 looking down. Fig. 6 is a perspective view of the magnet.

The box 1 is made of non-magnetic material of a proper size and shape to be inserted in any slot machine and to contain the parts to be described. This has the coin slot 2, a coin or slug being indicated at 3. A magnet 4 is fastened in fixed position to the top of the box, by a bolt 8 through holes 13 and lock nuts 14, one of its poles being located directly beside the slot 2. Located between the poles of the magnet is a stop member 5, comprising a plate of magnetic material pivoted as at 6 between pivots 11 and 12 supported by a frame 7 fixed to the magnet. The upper edge of this lock member has a groove 10, and the member is perforated as at 9 to increase the action of the magnetic flux between the poles. 45 Normally the attraction of the magnet will hold the stop member 5 in line between its poles and out of line with the slot, and when a coin is inserted it will slip past the stop and into the machine, as shown in Fig. 2. But 50 upon the insertion of a magnetic slug the

change of direction in the lines of force will cause the stop member to swing outwardly across the slot in position to engage and stop the slug, as shown in Fig. 3. As the slug cannot be inserted it must be removed.

The magnet is shown as a horse-shoe magnet but obviously other forms could be used, and various other changes may be made in the structure, within the scope of the invention.

I claim:

1. The combination with a casing having a coin slot, of a magnet fixed beside the slot, and a magnetic stop member pivoted between the poles of the magnet and adjacent the slot and normally held by the magnet out of line with the slot and adapted to swing across said slot upon the insertion of a magnetic slug therein.

2. The combination stated in claim 1, the stop member having a groove in its edge in which the slug will be engaged.

3. The combination stated in claim 1, the stop member comprising a plate of magnetic material with holes through the same.

4. The combination with a casing having a coin slot, of a magnet fixed to the casing, and having an upper pole beside the coin slot and a lower pole below the same, and a magnetic stop member pivoted to swing between the poles and normally held by the magnet out of line with the slot and arranged to swing into line with said slot upon the insertion of a magnetic slug beside the upper pole.

GUST POULAS.
